THE MORRIS PETERS CO., PHOTO-LITHO., WASHINGTON, D. C.

UNITED STATES PATENT OFFICE.

JOHN HERRICHT, OF CLEVELAND, OHIO, ASSIGNOR OF ONE-HALF TO
GUSTAV WALThER, OF SAME PLACE.

ELECTRIC-ARC LAMP.

SPECIFICATION forming part of Letters Patent No. 678,951, dated May 14, 1901.

Application filed December 26, 1900. Serial No. 41,050. (No model.)

To all whom it may concern:

Be it known that I, JOHN HERRICHT, a citizen of the United States, residing at Cleveland, in the county of Cuyahoga and State of Ohio, have invented certain new and useful Improvements in Arc-Lamps; and I do hereby declare the following to be a full, clear, and exact description of the invention, such as will enable others skilled in the art to which it applies to make and use the same, reference being had to the accompanying drawings, and to characters of reference marked thereon, which form a part of this specification.

This invention relates to arc-lamps, and more especially to that class of lamps known as "inclosed arc," using high current, designed for use as headlights, and has for its object means for focusing the arc in a reflector and other details of construction herein-after pointed out and particularly claimed.

Referring to the drawings, in which like parts are similarly designated, Figure 1 is a front view showing the lamp ready for trimming. Fig. 2 is a vertical central section of Fig. 1, some of the parts being shown in elevation. Fig. 3 is a detail perspective of the inner globe or bottle holder inverted, together with the carbon-guide therein. Fig. 4 is a detail in perspective, showing a modification of the bottle-holder, which is used at the end of the supporting-bracket of the lower carbon when I use a bottle open at both ends. Figs. 5 and 6 are modifications of means for adjusting the lamp. Fig. 7 is a section of a ring-clamp for securing a glass in the headlight-casing in front of the reflector.

Experience has shown that it is difficult to obtain a focusing-headlight using high-tension currents and capable of working between tensions of three hundred and one thousand volts.

Headlights heretofore constructed necessitated the use of large and expensive resistance-boxes, heating the car to a great extent, and when the current dropped, by reason of heavy traffic, extinguished the lamp. By the present construction I avoid the necessity of any resistance other than that ordinarily used in arc-lights, producing a lamp that cannot be jolted out, one that quickly and easily recovers itself after jolts due to the unevenness

of the track, and which is equally well adapted for street-railways using under or overhead circuits and locomotives.

Referring to Figs. 1 and 2, 10 is a reflector, secured by a screw 12 to a bracket 13 on the lower part of a base-board 11, designed to be hung on the dashboard or other desirable place on a car or secured on top of the smoke-box of a locomotive. In this base-board is formed a slot 14, extending from the top thereof to near the point where the reflector is secured. On each side of this slot is a guide rail or flange 141, between which slides the squared nut 201 on the bracket 20, and across the top of this slot is a bearing 15, through which works the spindle 16, carrying on its lower end a screw 17. The lower end of this screw is journaled in a bracket 18 at the lower end of the slot and may or may not carry a bevel-gearing 19. The nut 201 of the lamp-bracket 20 slides between the guide-rails 141 and is moved between the brackets 15 and 18 by the screw 17.

The upper end of the spindle 16 is squared at 21 for the reception of a suitable detachable operating key or handle, (not shown,) whereby the lamp can be focused relatively to the reflector from the top. It may, however, be desirable to move the lamp from the side, and to this end a second bevel-pinion 22, gearing with the pinion 19, secured to and operated by a cross-shaft 70, ending at the side of the headlight and operated by a similar key or handle 71.

The bracket 20 is secured to the lower spool-head 23 or to any other suitable rigid portion of the lamp. This lower spool-head, which is preferably, though not necessarily, of non-magnetic material, is secured to the spool-body 24, which is made of non-magnetic material, said body projecting somewhat below this spool-head. Secured to the upper end and forming a part of this spool-body 24 is the magnet 25, and secured to the magnet is an upper spool-head 26 of iron or brass. Between the spool-heads I wind a fine-wire winding 27 to a suitable depth and extending somewhat below the soft-iron magnet 25, and then continue over the entire spool with coarse-wire winding 28 in order to form a short intense field around the magnet and

less intense field beyond it, these windings being connected in series, as shown at 80. This arrangement of winding provides a greater number of ampere-turns around the 5 magnet 25 and less below it when the voltage or tension is high, thus increasing the magnetism of said magnet, drawing the armature 29 higher up to produce a longer arc; but when the voltage drops, due to great number 10 of cars being on the line, then the ampere-turns in the fine-wire winding will decrease, due to the decrease of voltage, and the armature will drop below the fine-wire winding and must be acted upon then by the coarse- 15 wire winding in order to hold it in a swinging position at a short arc. As soon as the voltage increases the strength of the magnet will increase and the armature will be immediately lifted to strike a longer arc.

20 Inside the spool-body 24 moves the armature 29, on the upper end of which is secured a carbon guide-tube 30, which has on its exterior threaded portion an adjustable ring-stop 31. This carbon guide-tube works 25 through the magnet and fits it snugly, as also does the armature the spool-body. Thus the space between the armature and the magnet has a cushioning effect, and the coöperating parts form a dash-pot within the body of the 30 spool.

The armature is provided near its top with a circumferential or cut-away portion 67, which forms a head to be strongly actuated upon, especially by the fine-wire winding, 35 and then a less magnetic portion at the neck in the armature, and then a more strongly magnetic portion below this groove. This arrangement allows a greater swing for the armature, provides automatic regulation when 40 the current drops, and insures a ready response to variations of current in the spool—that is, to variation of ampere-turns in the spool, due to drop of voltage.

In the lower end of the armature 29 is a 4 second guide-tube 32 and slotted on one side at 33. Screwed on this tube and abutting against the lower end of the armature is a sleeve or ring 34, which carries a pair of outwardly-flaring springs 35, having rollers 36 50 at their lower ends. To one of these springs is secured the carbon-clutch 37, taking through the slot 33 and engaging the carbon. I may make the tube 32 shorter and provide two clutch-jaws 34, one on each spring 35, that 55 will engage the carbon A below the lower end of said tube 32, thus providing a double clutch.

It will be observed that the tube 32 is adjustable in the armature 29 and also the ring 60 or sleeve 34 is adjustable on this tube, whereby the length of are, the throw of the armature, and the action of the springs can be adjusted. Secured below the lower magnet-head on the projecting threaded end of the 65 spool-body is a conical or flaring clutch-housing, provided in its circumference with a circumferential groove 72, into which the rollers

36 take at the limit of their downward travel, thereby causing the spread of the springs, releasing the upper carbon A from the clutch 70 and allowing it to drop. Onto this clutch-housing is secured a heat-shield or bottle-cap 38, through which passes the upper carbon, and secured to and insulated from it is a lower-carbon bracket 39, carrying in its end 75 the lower carbon B. Secured to the top of the spool and on the magnet 25 is a base 40, having a pocket 41 formed in a central projection 42. Around this projection 42 is placed the lamp resistance-coil 43, one end 80 of which is connected to the negative terminal of the lamp—to wit, the lamp-bracket 39—to feed lower carbon B. The other end of said resistance-coil is connected to a plug-pin 44, designed to enter a suitable socket in the 85 car.

One end of the spool-winding is connected to a plug 45, also designed to enter a socket in the car, and the other end is electrically connected to the lower spool-head and through 90 contacting parts to the carbon. Both of these pins 44 and 45, each of a different shape, are secured to a base 46 and simultaneously enter their sockets. The different shapes of the pins insure their insertion into proper sockets. 95

The upper bottle-holder and heat-shield (shown inverted in Fig. 3) comprise the body portion 38, whose threaded end 73 screws into the lower end of the clutch-housing, and plate 47, which forms the shield proper and abutment for the end of the bottle or inner globe, and also carries a raceway 48, in which are balls 49, forming a ball-bearing contact for the upper carbon. In order to insure constant contact with this carbon, I place around 105 this raceway and between the balls and the inner wall thereof a leaf-spring or sheet of spring metal 50, which by its tendency to coil will press the balls against the carbon. A suitable plate 51 fits over the raceway and 110 prevents the balls from falling out and is secured to the ball-bearing casing by means of screws 52. I, however, do not limit myself to this particular form of plate for securing the balls in place, as this may be a threaded plate 115 which fits into the end of the raceway. From the heat-shield 47 depends a suitable flange 53. This flange is slotted at two or more portions, as shown at 54, and has a perforation in it into which takes a thumb-screw 55. Surrounding this flange is a ring 56, carrying screws or pins 57, which take into the slots 54. This ring is made of a sufficiently-yielding material to allow a certain amount of expansion. The bottle is held against the heat-shield. The thumb-screw 55 is turned to move the ring eccentrically to the depending flange, whereby the screws or pins 57 and the thumb-screw 55 will be moved through the slots and hole in the depending flange and 120 take into the retaining-groove of the bottle. 125

When it is desirable to form a yielding connection for the bottle, as in the case of bottles open at both ends and of small diameter,

this ring is modified by cutting away a portion thereof between the lugs or screws 57, as shown in Fig. 4. Between the bottle and the pins or screws 57 and 55 I may insert a 5 yielding metallic strip, which will not fit closely into the groove and will yield sufficiently to the expansion of the bottle due to heating. Thus I avoid making the ring 56 of spring metal and may then cast it of iron.

10 Surrounding the entire lamp is a sheet-iron casing formed in two parts. The upper portion 86 is perforated to admit the stem 16 of the actuating-screw to pass through it, is secured to the projection 42 on the resistance- 15 base by means of a screw 57, and moves with the lamp. The lower portion 74 thereof is secured by bolts 58 to the base-plate 11 and is provided above the reflector with a door 59, swung outwardly when the lamp is lifted to 20 be trimmed and held closed by the upper box-like portion of the casing 86 when the lamp is in an operative position. In front of this casing 74 is a spring split ring 60, that has formed on either side of the split finger-grips 25 61, arranged to press together when inserting it into the groove 62 in the lower portion of the casing in front of the reflector. This ring has formed on its rear portion lugs 63, which hold the glass 64 between them and 30 the flange 65 on said ring. A grip 75 opposite the split aids in inserting the ring into the groove 62 in the casing 74. This arrangement allows the easy replacement of a glass in front of the reflector, the ring is removed 35 from the casing, the glass placed therein, and the finger-grips 61 pressed together to contract the ring 60, likewise drawing with it the lugs 63, thus making the entire glass frame of smaller diameter. The frame is then in- 40 serted into the groove 62 and allowed to expand; but this expansion is not sufficient to allow the glass to drop out of the ring. Should the metal of which the ring is made not have sufficient elasticity, I fasten to one 45 of the finger-grips a pin 76, whose free end slides in a hole in the other finger-grip. On this pin is a coil-spring 77, which will hold the ring securely sprung in its groove 62.

In lieu of the arrangement shown in Figs. 50 1 and 2 for lifting and lowering the lamp I may use a rack-and-pin motion (shown in Figs. 5 and 6) and focus both the lamp and the reflector.

Having thus described my invention, what 55 I claim as new, and desire to secure by Letters Patent, is—

1. The combination with a perforated stationary reflector, of a casing therefor, an arc-lamp organized to be moved through the perforations and focused in said reflector, and a 60 box-like portion for said lamp carried thereby and organized to telescope on the casing surrounding the reflector, substantially as described.

65 2. The combination with a perforated stationary reflector, a casing therefor and vertical door therein, an arc-lamp organized to

move through the perforations and be focused in said reflector, and a box-like casing secured to and movable with said lamp, organized to telescope a portion of the casing for said reflector and said door, substantially as described.

3. The combination with a perforated stationary reflector, a casing therefor and an arc-lamp movable through the perforations and focused in the reflector, a bracket secured to a solenoid-head of said lamp and a screw organized to move said bracket and lamp into focus, substantially as described.

75 4. In an arc-lamp, a solenoid comprising a non-magnetic tube, a magnet secured to one end thereof to form a continuation of said tube, both forming a spool-body, a magnetic spool-head secured to said magnet and a non-magnetic spool-head secured to said tube and suitable winding, substantially as and for the purpose set forth.

80 5. In an arc-lamp, a solenoid comprising a non-magnetic tube and lower spool-head, 90 said tube projecting below and adjustable in said head, a tubular magnet secured to said tube and with it forming the spool-body, a magnetic upper spool-head secured to the magnet, and suitable windings, substantially 95 as and for the purpose set forth.

6. In an arc-lamp, a solenoid comprising a spool, a fine-wire winding extending a portion of the length thereof and a coarse-wire winding in series therewith and extending 100 the remainder of the length of the spool, substantially as described.

7. In an arc-lamp, a solenoid comprising a spool, a fine-wire winding extending a portion of the length thereof, a coarse-wire winding in series therewith and extending the remainder of the length of said spool and arranged to cover also the fine-wire winding, substantially as described.

8. In an arc-lamp, a solenoid comprising a 110 spool-body, a magnet forming part of the spool-body, suitable heads, a fine-wire winding extending part of the length of the spool-body and a coarse-wire winding in series therewith and extending the remainder of the length of 115 said spool, substantially as described.

9. In an arc-lamp, a solenoid comprising a body portion, a magnet secured to one end thereof, a spool-head of magnetic material secured to said magnet and a lower head of 120 non-magnetic material in combination with a fine-wire winding extending part of the length of the spool and a coarse-wire winding in series therewith extending the remainder of the length of said spool and covering also the 125 fine-wire winding, substantially as described.

10. In an arc-lamp, the combination with a solenoid, a conical or flaring tube secured to said spool and recesses formed in said tube, an armature movable in said spool, a carbon-clutch secured to said armature, said clutch organized to be released by the recesses in said conical or flaring tube, substantially as described.

11. In an arc-lamp, in combination with a solenoid, a conical or flaring tube secured thereto and recesses in said tube, of an armature movable in said solenoid, a guide-tube 5 adjustable and projecting from said armature, a carbon-clutch adjustable on said guide-tube and organized to be released by the recesses in said conical or flaring tube, substantially as described.
12. In an arc-lamp, a solenoid comprising a spool-body, a magnet forming a part thereof, an armature movable in the spool-body, a guide-tube secured in the upper end of said armature and arranged to pass through the magnet and a stop adjustable on said tube in combination with a carbon-clutch carried by said armature and coöperating with the flaring tube to actuate the carbon, substantially as described.
13. In an arc-lamp, the combination with a solenoid, a conical or flaring tube secured at the bottom of said solenoid, of an armature in said solenoid, a carbon-clutch adjustable with relation to the armature and moved thereby comprising outwardly-flaring springs 25 engaging the interior surface of the conical tube, substantially as described.
14. In an arc-lamp, a solenoid, a conical or flaring tube secured thereto, in combination with an armature, a tube adjustably secured in the lower end of said armature, a sleeve 30 adjustable on said tube, outwardly - bent springs secured to said sleeve, rollers on the end of said springs and a clutch-jaw secured to one of said springs passing through the slot in said tube and engaging the carbon, substantially as described.
15. In an arc-lamp, a solenoid comprising a tube, a magnet secured to the end thereof 40 to form the spool-body, suitable heads, fine and coarse wire windings on said spool, a conical or flaring tube secured at the base of said spool, a releasing-space in said conical or flaring tube, an armature movable in said spool, a carbon-clutch, a guide-tube adjustable in the upper end of said armature, a stop adjustable on said tube, a guide adjustable in and secured to the lower portion of said armature, a ring adjustable on said tube, outwardly-flaring springs secured at one end to 50 said ring, a clutch-jaw on said springs the ends of said springs taking into the releasing-space in said conical or flaring tube, a carbon guide-tube adjustable in the upper end of said armature, a stop adjustable on said tube, a guide-tube adjustable in and secured to the lower portion of said armature, a ring adjustable on said tube, outwardly-flaring springs secured at one end to 55 said ring, a carbon-clutch jaw on said springs the ends of said springs taking into the releasing-space in said conical tube to withdraw the clutch-jaw from the carbon, substantially as described.
16. In an arc-lamp, comprising a solenoid having fine and coarse wire windings, a magnet forming a portion of the solenoid-body, a 60 clutch-housing secured below the solenoid, a bottle - cap or heat - shield secured to said clutch-housing, ball-bearing contacts in said bottle-cap for the upper carbon and a lower-carbon holder depending from the bottle-cap, substantially as described. 70
17. In an arc-lamp, the combination with the solenoid and its movable armature, of a clutch carried by said armature, a conical clutch-housing and a releasing-groove therein, said clutch coöperating with the housing to grip and release the carbon, substantially as described. 75
18. In an arc-lamp, the combination with the solenoid and its movable core, of a clutch-housing secured thereto, a circumferential releasing-groove in said housing, a clutch moved thereby comprising springs held at one end to the armature and the free ends thereof coöperating with the clutch-housing to cause them to grip and release the carbon, substantially as described. 80
19. In an arc-lamp, a ball-bearing carbon-contact comprising a raceway balls therein and a spring between said balls and raceway, substantially as described. 90
20. In an arc-lamp, a ball-bearing carbon-contact comprising a raceway, balls therein and a coil-spring between said balls and raceway, substantially as described. 95
21. In an arc-lamp, a ball-bearing carbon-contact comprising a raceway, balls therein and means for yieldingly holding the balls against the carbon, substantially as described. 100
22. In an arc-lamp, a ball-bearing carbon-contact comprising a raceway, balls therein and a coiled leaf-spring between said balls and raceway, substantially as described. 105
23. In an arc-lamp, a bottle-holder comprising a bottle-seat, a flange on said seat, slots therein, a ring surrounding said flange, pins in said ring projecting through the slots and means for moving the ring eccentrically to 110 said flange, substantially as described.
24. In an arc-lamp, a bottle-holder comprising a bottle-seat, a flange thereon, slots in said flange, a ring surrounding said flange, pins in said ring projecting through said slots and a thumb-screw in the ring also passing through the flange to move said ring eccentrically to the flange, substantially as described. 115
25. In an arc-lamp, a bottle-holder comprising a bottle-seat, a flange thereon, slots in and a ring surrounding said flange, pins adjustable in said ring and projecting through said slots, a thumb-screw in said ring projecting through the flange to move said ring eccentrically, substantially as described. 120
26. In an arc-lamp, a bottle-holder comprising a bottle-seat, a flange thereon, slots in said flange, a partial ring around said flange, pins therein projecting through the slots and means for moving said partial rings eccentrically to the bottle-holder, substantially as described. 125
27. In an arc-lamp, a bottle-cap, a ball-bearing carbon-contact therein, depending flange

and a pair of slots therein, a ring surrounding said flange, pins therein projecting through the slot and a thumb-screw through the ring and flange to move the former eccentrically to the latter, substantially as described.

5 28. In an arc-lamp, a reflector-glass holder comprising a split ring, a flange thereon, lugs on said ring and finger-grips at the split portion thereof arranged to hold the glass between the lugs and flange, substantially as described.

29. In an arc-lamp, the combination with the casing and grooved opening around the reflector thereof, of a glass-holder comprising a split ring, a flange thereon, lugs behind said flange, finger-grips on either side of the split ring and a spring between the finger-grips, the glass being held between said lugs and flange, substantially as described.

15 30. In an arc-lamp, a solenoid comprising a body portion, a magnet of the same external

and less internal diameter secured to and forming a continuation of said body portion, organized to act as both magnet and stop for a moving armature therein, substantially as 25 and for the purpose set forth.

31. In combination a base-board, a reflector secured thereto, a casing for said reflector having an offset, bolts passing through said reflector-casing and secured to the base-board, 30 a door hinged to said reflector-casing at the offset and an arc-lamp, a casing secured thereto and means for moving said lamp into the focus of said reflector and telescope the two casings, substantially as set forth. 35

In testimony that I claim the foregoing as my invention I have signed my name in presence of two subscribing witnesses.

JOHN HERRICHT.
